UNITED STATES PATENT OFFICE.

GEORGE MATCHELL, OF SOUTH PASADENA, CALIFORNIA.

FIRE, SMOKE, STEAM, AND AIR SHAFT.

1,014,969.

Specification of Letters Patent.

Patented Jan. 16, 1912.

Application filed September 29, 1910. Serial No. 584,567.

To all whom it may concern:

Be it known that I, GEORGE MATCHELL, a citizen of the United States, residing at South Pasadena, in the county of Los Angeles, State of California, have invented a new and useful device to be known as a "Fire, Smoke, Steam, and Air Shaft," of which the following is the specification:

This invention relates to improvements in flues or outlets for buildings of all kinds, steam-ships and the like, and it has for its object the provision of a non-combustible flue or duct adapted to be arranged in a building in such a manner that in the case of fire, the smoke, flames, steam, gases and the like will be drawn into said flue or chimney and carried upwardly outside the building or other structure where it may be safely discharged.

The invention comprises the novel constructions, combinations and arrangements of parts hereinafter described and claimed.

In the drawing, Figure 1 is a side elevation of a flue constructed in accordance with this invention, the said flue being shown as passing upwardly through a plurality of floors. Fig. 2 is a central vertical sectional view taken longitudinally through the upper portion of the flue. Fig. 3 is a horizontal cross sectional view through the flue or chimney taken upon the line 2-2 of Fig. 1.

Referring to the drawing in which the preferred form of flue embodying the invention has been shown, 1 indicates the shaft or main closure of the flue, 2 the inlet ports or ducts, and 3 the outlet discharge opening at the top.

The flue or duct forming the subject matter of this invention is particularly useful in buildings or other similar structures or in case of steam-ships and the like where there are one or more floors or decks, when fire breaks out and threatens to damage the structures.

The flue is constructed of fire resisting material, preferably cement or reinforced concrete, and may be made rectangular, cylindrical or any other desired shape as preferred. The main duct of the flue is preferably arranged to extend from the basement or bottom compartment of the structure or building upwardly through the floor 3 and the roof 4 thereof as illustrated in Fig. 1 of the drawing, the upper end of the flue being carried a sufficient height above the structure to prevent danger thereto, from

any flames that might escape from the top. The said duct or flue 1 is provided preferably just below each floor or deck with one or more inlet openings or ports 2 which lead into the hollow central portion of the flue. At each of said openings inclined converging floors or partial partitions 5 are arranged, leaving a central opening 6 for the draft maintained upwardly through the flue. These converging floors or partial partitions 5 insure the directing of the flames, smoke, steam and the like in an upward direction within the flue. The upper end of the flue is usually provided with a cover or cap plate 7 of any desired shape which rests upon standards 8 extending upwardly above the upper end of the said flue. Thus ample exit spaces as at 3 are provided at the discharge end of the flue or chimney. The inlet opening 2 may be provided with doors or closing means if preferred which can be arranged so as to be supported by fusible means. In the event of a fire the heat will melt the fusible supports and permit the opening of the doors.

As is well known in cases of fires in buildings or like structures or ship, the draft occasioned by shafts, stair-cases and the like tends to draw the flames and smoke at these points. By providing a flue having a better draft than such openings, the flames, smoke, bad fumes, and steam will be drawn into said flue and carried upwardly and outside of the building. By placing the openings 2 just below the floors or ceilings they are in the best position to receive and collect all of the smoke, steam and flames. Opportunity is thus given the fire departments to apply fire extinguishing means in the most effective manner.

What I claim is:

1. A fire and smoke flue for buildings adapted to extend from the bottom through all the floors free from the walls thereof, and through the top of the building, said flue having relatively large inlet apertures just below the ceilings of each floor, the said apertures extending practically entirely around the flue so as to employ the entire capacity of the flue in accommodating the escape of smoke, gas, or the like, in case of fire, and inclined funnel-shaped floors arranged opposite each of said openings and extending above the plane of the ceilings, the inclination thereof tending to direct the smoke upwardly in the flue.

2. An integral single flue fire and smoke stack for buildings, adapted to extend from the bottom of a building through all the floors and top thereof, said flue having inlet
5 apertures arranged just below the ceiling of each floor, the said apertures extending practically entirely around the flue, so as to secure a converging draft to the extent of the capacity of the flue in accommodating
10 the escape of smoke, gases and the like in the case of fire, and inclined floors arranged

at each of said openings, the inward projection of said floors tending to facilitate the entrance of smoke and flames into the flue at the successive floors without the entrance 1 thereof being cut off by the column of materials already moving in said flue.

GEORGE MATCHELL.
